UNITED STATES PATENT OFFICE.

WILLIAM W. DEAN, OF CHICAGO, ILLINOIS.

IGNITION SYSTEM FOR INTERNAL-COMBUSTION ENGINES.

1,145,232.

Specification of Letters Patent.

Patented July 6, 1915.

Application filed August 23, 1912. Serial No. 716,704.

To all whom it may concern:

Be it known that I, WILLIAM W. DEAN, a citizen of the United States, residing at Chicago, in the county of Cook and State of Illinois, have invented new and useful Improvements in Ignition Systems for Internal-Combustion Engines, of which the following is a full, clear, concise, and exact description, reference being had to the accompanying drawing, forming a part of this specification.

My invention relates to improvements in ignition systems for internal combustion engines, and has particular reference to means for automatically advancing and retarding the spark, the function of which is well known to the art.

In the drawings, which illustrate one embodiment of my invention Figure 1 is a sectional view taken longitudinally through the center of the apparatus, which in the present instance is designed for a four-cylinder engine; Fig. 2 is a cross-sectional view taken on the line 2—2 of Fig. 1; Fig. 25 3 is a similar view taken on the line 3—3 of Fig. 1; Fig. 4 is an end elevation showing the upper end of the apparatus of Fig. 1; and Fig. 5 is a diagrammatic view showing the electric circuits involved.

30 A cylindrical casing 10 supported in a stationary position in any desired way with its longitudinal axis preferably vertical, affords at its ends suitable bearings for the shaft 11, which shaft may be suitably connected to the cam shaft of the engine, or driven in any desired way at half the speed of the crank shaft of the engine. Between these bearings the shaft 11 is provided with a rectangular portion 12 within which is 35 pivoted a centrifugal governor ring 13 on suitable pivot screws 14 passing through the ends of the rectangular portion 12 and into diametrically opposite pivot recesses in the peripheral edge of said ring 13.

40 The upper end of the shaft 11 is provided with a central bore extending to and into the rectangular part 12 and within this bore is a sliding stem 15 which has an enlarged head 16 fitting said bore and longitudinally 45 slideable therein. This head is provided with a pin 17 extending through a slot in the shaft 11 to limit the movement of said stem longitudinally and to prevent its rotation with respect to the shaft. The inner end of 50 the stem is provided with an arm 18 extending substantially at right angles thereto and

55 with its outer end rounded and projecting downwardly, as shown, to engage the adjacent face of the governor ring 13. This arm is shown as an extension from a ring or sleeve mounted on the reduced end of the stem 15 at the lower end of the head 16, and secured thereon by means of a suitable pin 19. The upper end of this stem 15 passes through a suitable bushing 20 secured in the end of the shaft 11, as by a screw 21, and between this bushing and the head 16 of the stem is located a coiled spring 22 which is placed under tension to cause the end of the arm 18 to constantly bear against the side of the ring 13 with the desired pressure.

60 On the stem 15 outside the casing 10 is fixedly secured a cylindrical cam member 23 preferably insulated from said stem and having on its surface spiral cam ribs 24 corresponding in number to the number of cylinders in the engine, in this instance four. Also on the end of the casing 10 and adjacent the cam 23 (see Fig. 2) are located the make-and-break contacts ordinarily termed 65 timer contacts. These consist of a stationary screw contact 25 and a spring contact 26. Both are suitably supported in posts carried by but insulated from the end of the casing, and are connected with the 70 electric circuit conductors in any desired way but preferably by suitably fixed conductors leading from said contacts or contact parts to fixed binding terminals mounted on the outside of the casing. The free 75 end of the spring contact 26 is bent, as at 27, to form a projection which engages the spiral cam ribs 24 as the cam rotates, and is thereby lifted into engagement with the contact screw 25 to make the circuit. The tension of the spring is so adjusted that when the cam rib passes from beneath the projection 27, the spring contact snaps away from the contact 25 and breaks the circuit.

80 It will be apparent from the description 85 so far given that as the speed of the shaft 11 increases the governor ring 13 tends to assume a position perpendicular to the axis of the shaft, and that position which this ring does assume at any particular time is 90 dependent on the speed of the shaft at that time. As this ring moves into its perpendicular position the arm 18 is engaged by the side of the ring and the sliding stem 15 95 is moved upwardly, carrying with it the 100 cam 23. As the cam 23 moves upwardly, the ribs 24 on said cam, owing to their spiral

relation, engage the projection 27 on the spring 26 that much sooner in the rotation of the cam, and thus the make-and-break of the electric circuit is advanced accordingly 5 and in proportion to the speed of the engine. The timing of the spark is thus automatically advanced and retarded with the rise and fall of the speed of the engine.

In order that the electric current may be 10 suitably distributed to the different cylinders of the engine, I provide an insulating casing or housing 28 fitting upon and secured to the end of the casing 10. This casing may be of hard rubber or composition 15 suitable for the purpose. On the outer end of the casing are located four binding posts or terminals 29 from which wires or cables lead to the various spark plugs of the engine. A central post 30 connects externally 20 with the high tension wire or cable leading from the secondary of the transformer or induction coil. The binding posts 29 are connected inside the casing with suitable conducting strips 31 which are embedded in 25 the material of the cylindrical wall of the casing, so as to present an even surface with the inside face of said casing. These strips are arranged spirally inside of the casing, and at the same relative angle or pitch as 30 the spiral ribs 24 on the cam 23. A distributing arm 32, also of hard rubber or suitable insulating composition is carried on the outer end of the stem 15 outside of the cam 23, and is adapted to rotate with the shaft 11. The pin 33 on the outer face of the cam 23 engages the head of said arm 32 and insures its rotation with the said stem and shaft. In the end of the arm 32 is located a 35 carbon brush 34 of usual construction, said brush being square in cross-section and fitting within a square metallic casing 35 embedded in the end of the arm 32 and containing a spiral spring 36 adapted to press said carbon contact 34 outwardly and maintain it in engagement with the inside wall 40 of the casing 28 and the strips 31. This casing or tube 35 is connected by a suitable electric conductor 37 with a small plate 38 on the outer side of said arm opposite the end 45 of the stem 15. A similar carbon brush 39 carried in the central post 30 bears upon this contact plate 38 to complete the circuit from the binding post 30 to and through the distributing arm 32 and the brush 34. The 50 brush 39, like the brush 34, is carried in a metallic casing 40 embedded in the surrounding material, and is pressed forward by a coiled spring 41 extending between said brush 39 and the inner end of the binding post 30. Fig. 5 illustrates diagrammatically 55 these various circuits. The battery is shown at 42, the transformer or induction coil at 43, and the spark plugs of the various cylinders at 44. A switch 45 is provided in the 60 primary circuit. As will be apparent from 65

this figure, the primary circuit includes the battery 42, the primary winding of the transformer 43, the switch 45 and the make-and-break contacts 25 and 26. The secondary or high tension circuit includes the secondary winding of the transformer 43, the distributing contact arm 32, the coöperating segments 31 and the spark plugs 44. If now the circuit be closed at the contacts 25 and 70 26 by the cam 23 the current from the battery flows in the primary circuit and energizes the primary winding of the transformer or induction coil. The circuit is then suddenly broken and a strong high tension current is induced in the secondary circuit. 75 This current flows by way of the distributor arm 32 and the appropriate contact 31 with which it is then in contact to the corresponding spark plug 44 where the spark is produced to ignite the charge in the engine cylinder. It is likewise apparent that as the speed of the shaft 11 increases and the time of making and breaking the circuit through the contacts 25 and 26 is advanced, the position of the distributor arm 32 is likewise 80 advanced so that the brush 34 is always in the proper position upon one of the contact strips 31 to appropriately complete the secondary circuit at the time of the break in the primary circuit, whether said break is advanced to its highest position or retarded to its lowest position, or is at any intermediate position. Thus while the brush 34 is always in full electric contact with the corresponding contact strip 31 to entirely complete the electric circuit at that point when the circuit is made and broken, it is not necessary to locate said strips close together and there is no danger whatever of the spark being drawn across from one to the other, as 85 would be the case if it were necessary to make the contacts 31 in the form of segments large enough to accommodate the varying positions of the spark.

Various changes, alterations and substitutions may be made in my invention, without departing from the principle or scope thereof, as set forth in the appended claims.

While I have shown this invention in connection with a battery system of ignition, it 115 is apparent that it may be employed also in magneto systems of ignition.

Having thus described my invention, what I claim as new and desire to secure by Letters Patent, is—

1. In an ignition system for multiple cylinder internal combustion engines, the combination with a plurality of contact strips corresponding to the number of cylinders of the engine, of a contact rotatable with respect thereto and successively making contact therewith, said contact strips being spirally arranged with respect to the axis of rotation, means for advancing and retarding the spark, and means for simultaneously 125

moving said rotatable contact axially to advance and retard the same in accordance with the advancement and retardation of said spark, whereby the said successive contacts are completed in timed relation with the spark.

2. In an ignition system for multiple cylinder internal combustion engines, a shaft driven at a speed proportional to the speed 10 of the engine, a longitudinally sliding stem in said shaft and revolving therewith, a balanced governor carried by said shaft and serving to vary the position of said stem therein according to the speed of the engine, 15 a cam on said stem having spirally arranged cam surfaces thereon, and a make-and-break set of electric contacts mounted adjacent said cam and operated by said cam surfaces.

3. In an ignition system for multiple cylinder internal combustion engines, a shaft driven by the engine, a longitudinally sliding member connected to said shaft and rotating therewith, a governor also driven by the engine and serving to control the longitudinal 25 position of said member, make-and-break contacts operated by said member and arranged to be advanced or retarded in their action in accordance with the longitudinal position of said member, a contact arm also carried by said member and reciprocating therewith, a plurality of spirally arranged contact strips concentric with said arm and adapted to be successively engaged by said arm in its rotation, whereby when the spark 30 is advanced or retarded by the governor the contact of said arm and said strips will be correspondingly advanced or retarded.

4. In an ignition system for multiple cylinder internal combustion engines, a casing, 40 a shaft mounted in said casing and driven by the engine, a sliding stem in said shaft and rotating therewith, a balanced governor carried by said shaft and serving to shift

said stem according to the speed of rotation of the shaft, a cam mounted on the end of 45 said stem, and having spirally arranged cam surfaces thereon, a set of make-and-break contacts mounted on the casing adjacent the said cam and operated by the cam surfaces thereon, a contact arm mounted on the said stem and rotating therewith, a second casing mounted on said first mentioned casing, contact strips mounted on the inside of said casing and adapted to be engaged by said contact arm in its rotation, said strips being 50 also arranged spirally corresponding to the said spiral cam surfaces, whereby when the spark is advanced or retarded, the contacts made by said arm in its rotation are correspondingly advanced or retarded.

5. In an ignition system for multiple cylinder internal combustion engines, the combination with a casing, of a shaft driven at a speed proportionate to the speed of the engine, a cam mounted in said casing and rotated by said shaft and having a plurality of spirally arranged cam surfaces thereon, a make and break set of electric contacts mounted in said casing adjacent said cam and operated by said cam surfaces, a plurality of spirally arranged contacts mounted within said casing, and an arm rotatable in said casing with said cam having a contact at the end thereof arranged to engage during its rotation said spirally arranged contacts, said cam and arm having an axial movement corresponding to the speed of the engine.

In witness whereof, I have hereunto subscribed my name in the presence of two witnesses.
